Primary Examiner — Ryan Harvey(74) *Attorney, Agent, or Firm* — Banner & Witcoff, Ltd.(57) **CLAIM**

The ornamental design for a gaming terminal, as shown and described.

DESCRIPTION

FIG. 1 is a front perspective view of a gaming terminal showing myour new design;

FIG. 2 is a front view thereof;

FIG. 3 is a left side view thereof;

FIG. 4 is a right side view thereof; and,

FIG. 5 is a top view thereof.

The broken line showing of the four unshaded circular regions and the unshaded shaded areas therein represent unclaimed subject matter and form no part of the claimed design. The broken lines immediately adjacent to the shaded area represents boundaries of the design and form no part thereof. The broken line showing of the remainder of the gaming terminal represents unclaimed subject matter and forms no part of the claimed design.

1 Claim, 5 Drawing Sheets# US D855,112 S
